UNITED STATES PATENT OFFICE

HAROLD V. ATWELL, OF WHITING, INDIANA, ASSIGNOR TO STANDARD OIL COMPANY, OF WHITING, INDIANA, A CORPORATION OF INDIANA

PREVENTION OF EVAPORATION LOSSES

Original application filed April 25, 1927, Serial No. 186,478. Divided and this application filed March 18, 1929. Serial No. 347,961.

This invention relates to the prevention of evaporation losses, particularly from gasoline or other petroleum products containing volatile fractions. This application forms 5 a division of my application, Serial No. 186,478.

The invention will be readily understood from the following description illustrated by the accompanying drawings, in which 10 Fig. 1 is an elevation of a general apparatus embodying the invention, and

Fig. 2 is a sectional elevation of the control apparatus.

Referring to the drawings, and particularly Fig. 1, 10 are storage tanks for the volatile liquid and 11 is a vapor storage device which may be a gas-holder of conventional form. 12 is the control apparatus, which will be fully described hereinafter. 20 From the control apparatus, line 13 leads vapors to pump 14, by which they are forced to the gas-holder 11. The pump 14 is preferably controlled and operated so as to maintain a slight vacuum in the line 13. A line 25 15 leads from the gas-holder 11 to the control apparatus 12. Lines 16 lead from the vapor spaces of the tanks of the storage system to the control apparatus 12.

In the illustration given, 17 represents a 20 motor which comprises an inverted cup 18 pivotally mounted within a chamber 19 by means of studs 20 which rest on brackets 21, provided with V-shaped slots. The brackets are mounted on opposite sides of the chamber 19. The inverted cup 18 is provided with steeply depending sides, since it is intended that they shall not completely emerge from the liquid in which they are immersed. The studs 20 are considerably off center so as to provide a considerably greater pressure surface on one side than the other. On its shorter side and preferably internally the inverted cup 18 is provided with a weight 22 so as to balance substantially the greater mass of the larger side of the cup. Beneath the inverted cup 18, a pipe 23 extends upwardly from the bottom of the chamber 19, said pipe terminating above the level of the liquid in said chamber so that the under surface of

the inverted cup 18 is exposed to atmospheric pressure.

The chamber 19 is provided with a cover 24 which is fastened thereto in an air-tight manner, for example, by bolts, with an intervening gasket. From the cover 24 ascend 55 hollow, preferably cylindrical, extensions 25 and 26, suitably integral with said cover and located over the short and long ends respectively of the inverted cup 18. Within the 60 extensions 25 and 26, near their lower ends, are provided peripheral channels 27 and 28, adapted to contain sealing liquid. Within the upper part of the extensions 25 and 26 are provided cylindrical members 29 and 30, 65 provided at their lower ends with internal peripheral channels 31 and 32, adapted to receive sealing liquid. Above the cylindrical members 29 and 30 are located covers 33 and 34. The members 25, 29 and 33 are provided with registering flanges so that they may be bolted together in air-tight manner. The members 26, 30 and 34 likewise, are provided with registering flanges so that they may be similarly bolted together. Within 70 the extension 25 are provided an inverted cup 35 having a skirt depending into the sealing liquid in channel 31 and an inverted cup 36 of equal cross-sectional area, having a skirt 75 depending into the sealing liquid in channel 27. The cups 35 and 36 are fixedly mounted on a hollow stem 37 which extends downwardly to the upper surface of the inverted cup 18. The stem 37 is open at its upper end and is provided with a closed, rounded lower 80 end for cooperation with the inverted cup 18. Between the cup 36 and its lower end, the stem 37 is perforated at 38 so that the pressure of the vapors above the inverted cup 18 is exerted on the upper side of cup 35, through 85 perforations 38 and hollow stem 37. The cup 35 and channel 31 are preferably deeper than the cup 36 and channel 27, since it is preferred to vent exclusively through the lower seal. From the cover 33, depends a 90 guide-rod 39 which extends into the hollow stem 37, the rod being smaller than the interior of the stem so that pressure communication is not interrupted thereby.

Within the extension 26 a similar valve cup

assemblage is provided, comprising an inverted cup 40 having a skirt depending into channel 32 and an inverted cup 41 of equal cross-sectional area, having a skirt depending into the sealing liquid in channel 28. The 5 cups 40 and 41 are fixedly mounted on a hollow stem 42 which extends downwardly to the upper surface of the inverted cup 18. The stem 42 is open at its upper end and is provided with a closed, rounded, lower end 10 for cooperation with the inverted cup 18. Between the cup 41 and its lower end the stem 42 is perforated at 43 so that the pressure of the vapors above the inverted cup 18 15 is exerted on the upper side of cup 40, through perforations 43 and hollow stem 42. The cup 40 and channel 32 are preferably deeper than the cup 41 and channel 28, since it is preferred to vent exclusively through the 20 lower seal. From the cover 34 depends a guide-rod 44 which extends into the hollow stem 42, the rod being smaller than the interior of the stem, so that pressure communication is not interrupted thereby. The vapor 25 pipe 16 from the liquid storage system communicates with the upper part of chamber 19, being preferably connected to the cover 24 thereof. The vacuum line 13 is connected to the extension 25 between the cups 35 and 36, and the pressure line 15 is connected to the 30 extension 26 between the cups 40 and 41.

The operation of the apparatus is as follows:

When the pressure in the liquid storage 35 system exceeds atmospheric pressure by an amount which may be predetermined by the mass of the stem 37 and the cups 35 and 36 carried thereby, the excess pressure on the larger side of the inverted cup 18 causes it to 40 tilt downwardly, raising the shorter side of the cup 18 and thereby the stem 37 and inverted cups 35 and 36, until the latter is withdrawn from the liquid in channel 27, whereupon vapors pass from the liquid storage 45 system through pipes 16 and extension 25 to the vacuum line 13 from which they are removed into the gas-holder 11 by pump 14. This continues until the excessive pressure in the liquid storage system is relieved and 50 is insufficient to maintain the cup 18 tilted, whereupon the cup 36 returns to its closed position.

When the pressure in the liquid storage 55 system falls below atmospheric pressure by an amount which may be predetermined by the mass of the stem 42 and the cups 40 and 41, carried thereby, the excess pressure on the larger side of the inverted cup 18 causes it to tilt upwardly, raising the stem 42 and inverted cups 40 and 41 until the latter is withdrawn from the liquid in channel 28, whereupon vapors pass from the gas-holder 11 by pipe 15, extension 26 and chamber 19 into a pipe 16 by means of which the vapors 60 pass to the liquid storage system. This con-

tinues until the excessive partial vacuum in the storage system is relieved and is insufficient to maintain the cup 18 tilted, whereupon the cup 41 returns to its closed position.

Since the pressure of the liquid space exerts an equal force downwardly on cup 35 and upwardly on cup 36 and since the pressure in the vacuum line acts equally and oppositely on these cups, the control of valve 36 70 is completely independent of these pressures and is operated solely by the difference between the atmospheric and liquid space pressures acting on motor 17. Likewise, valve 41 is operated by the difference between the atmospheric and liquid space pressures acting on motor 17, and is completely independent of the liquid space and gas-holder pressures.

While the invention has been described in 85 connection with the details of specific embodiments thereof, it is not intended that such details shall be regarded as limitations upon the scope of the invention, except in so far as included in the accompanying claims. 90

What I regard as new, and desire to secure by Letters Patent, is:

1. In combination, a chamber, an inverted cup therein pivoted off its center of pressure, having sides extending into sealing liquid and being exposed on one side to atmospheric pressure and on the other side to the pressure in a liquid storage system, two conduits leading into said chamber, valves adapted to close said conduits, operating 100 means between said valves and the inverted cup, an inverted cup corresponding to each of said valves and having a depending skirt extending into sealing liquid, a hollow stem connecting each of said valves to the corresponding cup whereby the pressures on the valves are counterbalanced by the opposite pressures on said cups.

2. In combination, a chamber, a motor 110 therein adapted to be moved by variations in pressure, a vertical extension of said chamber provided with two superimposed channels for sealing liquid, an inverted cup in each of said channels, each cup being mounted on a hollow stem which opens into said chamber and into the extension above the upper inverted cup and extends to a moving part of said motor, a conduit leading into said chamber and a conduit leading into said extension between said channels.

3. In combination, a chamber, an inverted cup therein, pivoted off its center pressure, having its sides extending into sealing liquid, a pipe leading from the underside of the inverted cup to the atmosphere, and a conduit 125 leading into said chamber, said chamber being provided near each end of the inverted cup with an upward extension, each extension being provided with a pair of superimposed channels adapted to receive sealing liq- 130

uid, and a conduit leading into each extension between the pairs of superimposed channels, inverted cups seating in said channels, a hollow spindle in each extension, on which each pair of superimposed cups is mounted, said hollow spindle cooperating with the surface of the tilting inverted cup and opening into said chamber and into said extension above the upper cup.

10. 4. In an apparatus of the type described, a balanced valve comprising a vertical casing, a pair of superimposed channels therein adapted to receive sealing liquid, a pair of inverted cups in said channels of substantially 15 equal cross-sectional area, a hollow member on which said valves are mounted, said member making communication between the space above the upper cup and the space below the lower cup, and a conduit communicating with said casing between said channels.

5. A balanced valve for controlling fluid flow, comprising a vertical casing closed at one end and open at the other end, a pair of 20 superimposed channels in said casing adapted to receive sealing liquid, a pair of inverted cups in said channels of substantially equal cross-sectional area, a hollow member on which said valves are mounted, said member 25 making communication between the space above the upper cup and the space below the lower cup, and a conduit communicating with said casing between said channels, the channel and cup nearer the closed end of said casing being substantially deeper than the channel and cup nearer the open end, whereby 30 fluid passage occurs between the latter channel and cup.

6. A balanced valve structure for controlling passage of vapor through a conduit, comprising a casing, an interior channel in said casing adapted to receive sealing liquid, a sleeve removably mounted in said casing and provided with an interior channel adapted to 45 receive sealing liquid, a pair of inverted cups of substantially equal cross-sectional area in said channels, a hollow member on which said cups are mounted, said member being open to the spaces above and below the upper and 50 lower cups respectively, and a conduit communicating with the casing between the first said channel and said sleeve.

7. In a balanced valve structure, means constituting a pair of superimposed liquid 55 channels, a pair of inverted cups of substantially equal cross-sectional area, cooperating therewith, a hollow stem carrying said cups and open to the upperside of the upper cup and the lowerside of the lower cup, the means 60 constituting the upper channel being removable from the structure, whereby the cups and stem are likewise removable.

8. In combination, a chamber and inverted cup therein pivoted off its center of pressure, 65 having sides extending into sealing liquid

and being exposed on one side to atmospheric pressure and on the other side to the pressure in a liquid storage system, two conduits leading into said chamber, valves closing said conduit, and a stem connecting each of said valves to the inverted cup, said stem cooperating with the surface of the inverted cup to open and close said valves. 70

9. A balanced valve construction for controlling the passage of vapor through a conduit, comprising a casing, a pair of superimposed liquid channels therein, a pair of inverted cups co-operating therewith, one of said cups being less deep than the other and adapted to serve as a valve, a stem carrying 75 said cups reciprocably mounted in said casing, and means for actuating said stem.

10. In a balanced valve structure, a casing, a pair of superimposed liquid channels, a pair of inverted cups co-operating therewith, a 80 hollow stem carrying both of said cups, and a guide rod supported in said casing and extending into said hollow stem.

11. In combination, a casing affording a chamber, a motor therein adapted to be moved by variations in pressure, a vertical extension of said chamber providing a pair of superimposed liquid channels, and a pair of inverted cups cooperating therewith, said cups being carried by a slidably mounted stem 90 which is hollow, said stem opening into said chamber and into the extension above the upper inverted cup and being actuated by a moving part of said motor. 95

In witness whereof, I have hereunto set my hand this 13th day of March, 1929.

HAROLD V. ATWELL.
